UNITED STATES PATENT OFFICE.

JOHN HENRY MILLER, JR., OF IRWIN, PENNSYLVANIA.

GAS-PRODUCING APPARATUS.

SPECIFICATION forming part of Letters Patent No. 703,943, dated July 1, 1902.

Application filed January 24, 1902. Serial No. 91,067. (No model.)

To all whom it may concern:

Be it known that I, JOHN HENRY MILLER, Jr., residing at Irwin, in the county of Westmoreland and State of Pennsylvania, have invented a new and Improved Gas-Producing Apparatus, of which the following is a specification.

My invention is an improved gas-producing means, more particularly adapted for making illuminating-gas, and the same comprehends a novel, coöperative, and peculiar arrangement of parts, all of which will hereinafter be fully described, and specifically pointed out in the appended claims, reference being had to the accompanying drawings, in which—

Figure 1 is a side elevation of my type of gas apparatus looking in the direction of arrow *a* in Fig. 2, portions being broken away to better illustrate some of the parts. Fig. 2 is a plan view thereof. Fig. 3 is a horizontal section of the same, taken practically on the line 3 3 of Fig. 1. Fig. 4 is a horizontal section taken on the line 4 4 of Fig. 1. Fig. 5 is an end elevation of the apparatus, one of 25 the generating-chambers being shown partly in cross-section. Fig. 6 is a detail side view, partly in section, the latter being taken on the line 6 6 of Fig. 5 and looking in the direction of arrow *b* on Fig. 5.

In the practical construction my invention includes a number of generating-compartments consisting of perpendicular chambers, three being shown in the drawings and designated by 1, 2, and 3. These chambers have 35 a like construction, are disposed transversely of the complete structure and in parallel planes, their upper or crown portion being arched, as at 1^a, where they merge with the front and rear walls, (indicated by *ww*.) One 40 of the said chambers, preferably the one designated as No. 1, communicates at the top with the vaporizing-chamber D for reasons presently explained.

Each of the chambers 1, 2, and 3 has three 45 doors *d* *d'* *d''*, disposed in different horizontal planes, the upper one *d* of which covers the filling or feed opening *f* in the front wall *w*, the next lower end *d'* covers the clinker-opening *f'*, and the lowermost one *d''* the ash-pit 50 opening *f''*.

Each chamber 1, 2, and 3 has a grate *g* in a plane just below the opening *f'*, as clearly

shown in Fig. 5, and the several doors *d* *d'* *d''* each have the usual latch devices, as shown. 55 4 designates a horizontally-disposed chamber which extends lengthwise of the apparatus, and said chamber projects through the rear ends of the several chambers 1, 2, and 3 and is located just under the arch or crown of said chambers 1, 2, and 3, with its bottom 60 in a plane above the bottom of the filling-opening *f*, so that the fuel can be thrown in the chambers 1, 2, and 3 and filled up to a point under the aforesaid chamber 4, as will be clearly understood by reference to Fig. 5. 65 The chamber 4 is formed of an approximately semicircular shell made of fire-clay, like a retort for gas, and which extends through the end wall *w*² and into the end wall *w*³, at which point it is closed by a cap-plate E, bolted to 70 the said shell. At the opposite end an extension 4^b is bolted to the shell 4^a, in the head of which is a door or manhole 4^c, and with this extension communicates a stack B', having a cut-off or closure valve b' at the top. 75

P designates the gas-offtake pipe, connected with the extension 4^b and which discharges into the water seal or purifying-tank G of any approved construction and having the usual offtake or house-supply pipe P' and 80 water-pipe P², as shown.

By providing a steel shell 4^a and mounting it coöperatively with the other parts, as described, I can in case of necessity or desirability remove said shell by disconnecting 85 the extension 4^b therefrom and removing the cap-plate E and substituting a new shell therefor.

By referring now to Fig. 3 it will be noticed the vertical walls that separate chambers 1, 90 2, and 3 have openings *o* *o'* to provide for circulation of the gaseous products from the vaporizing-chamber D to chamber 1 through chamber 2 and from thence to chamber 3, and from said chamber 3 the products pass up into 95 the chamber 4, the latter having an inlet 4^e directly over the chamber 3, as clearly shown in Fig. 3.

The vaporizing-chamber D, before referred to, extends vertically above the chamber 1, 100 and said chamber D is in the nature of a wide stack, its upper end having a stack-piece proper (indicated by B) and provided with a closure-valve, as shown.

The chamber D has openings normally closed by hinged doors 8 8^a, and the interior of chamber D is made up of checker-brick-work (indicated by D^X) to provide a maximum heat-surface for the oil to pass over.

H designates the valved crude-mineral-oil feed pipe that discharges into the upper part of chamber D, and 10 10^a 10^b designate the air-blast tubes for the chambers 1, 2, and 3, and 11 11^a 11^b the valved steam-jet pipes for injecting steam under the grate-surfaces of said chambers 1, 2, and 3.

The manner in which my producing apparatus is set in operation is best explained as follows: The chambers 1, 2, and 3 are first filled with hard coal or coke within one foot of the bottom of the top openings f. The doors to said chambers are then closed and the closure-valves on the stacks B and B' are opened. The blast-pipes that feed under the grates g are now opened and maintained until the blast is run up to a bright-orange heat. The blast-pipes are then closed and soft nut-coal is charged through the feed-openings f onto the top of fire to the desired height. The doors d are then closed, as are also the valves for stacks B and B', steam turned on under grates g, and oil turned into the vaporizing-chamber D. Tar is then fed into No. 1 chamber by any suitable injector means. The apparatus will now be generating gas, the time of runs in the practical operation of my invention being from ten to twenty-five minutes.

By arranging the several parts as described and charging the apparatus in the manner stated the nitrogen is driven off and the desired gas product is left practically free of nitrogen. Furthermore, all of the heavy carbon is extracted from the tar fed into the chamber 1, as before described, by reason of its running through the several chambers. Again, my improved arrangement of parts presents a very large amount of heating-surface. The oil is vaporized in chamber D and caused to pass through the several chambers 1, 2, 3, and 4, where it intermixes with the other products, the gaseous mixture passing from the chamber 4 to the seal and purifying devices.

During blasting the heat passes out through chambers 1, 2, 3, and 4, chamber D, and the stacks B B'. The greatest part, however, goes up through the checker-brickwork in the chamber D.

In practice the nut-coal that is charged into the upright chambers 1, 2, and 3 is not drawn out, but remains in said chambers to keep up a fire-bed. Crude oil is mixed with the nut-coal for enriching.

In my construction of apparatus I am enabled to obtain five hundred to six hundred

heat units as against three hundred and fifty units secured in water-gas and also have a complete combination of coal and water gas produced under a uniform and regular candle-power. It should also be stated that in operation when gas is making it passes through the partitions between the several chambers 1, 2, and 3, which helps to break the small globules, and thereby more thoroughly fix the gas.

In charging the chambers 1, 2, and 3 with soft nut-coal, as stated, I have the advantage of spreading it all over the surface of the fire, and after the gas is all drawn out of said coal it remains on the fire, and thereby no heat is lost drawing it out and substituting cold fuel. Again, by providing for charging the nut-coal with a shovel the same can be easily made even over the surface of the fire and not in piles, as is usually the case when fed by magazines and hoppers.

Having thus described my invention, what I claim, and desire to secure by Letters Patent, is—

1. In a gas-producer of the character described, the combination with the main structure including the vertical walls thereof, a vertically-disposed generating-chamber, a valved stack therefor, and means for feeding vaporized oil into the said vertical chamber; of the horizontal chamber, consisting of a metal shell endwise slidable and detachably supported in the vertical walls of the main structure, said shell having an intake in communication with the generating-chamber, a closure-cap for one end of said shell, and an extension for the other end, provided with a valved draft flue or stack and gas-outlet, all being arranged substantially as shown and for the purposes described.

2. In a gas-producing apparatus of the character described, comprising in combination, a main structure, having a series of parallel vertically-disposed generating-chambers 1, 2 and 3, a blast and a steam-injector means co-operatively joined therewith, the division-walls between the chambers 1, 2 and 3 having openings for joining said chambers, the horizontal chamber 4, having an opening in communication with the chamber 3, and having an extension provided with a valved stack and an outlet, the vaporizer-chamber D, in communication with the chamber 1, and having a valved draft-stack and an oil-supply for said chamber D, all being arranged substantially as shown and for the purposes described.
